UNITED STATES PATENT OFFICE.

LOUIS W. BERGMAN, OF NEW YORK, N. Y.

LOOSE-LEAF BINDER.

Application filed March 29, 1921. Serial No. 456,555.

To all whom it may concern:

Be it known that LOUIS W. BERGMAN, a citizen of the United States of America, residing at New York, in the county of New York and State of New York, has invented certain new and useful Improvements in Loose-Leaf Binders, of which the following is a specification.

The present invention relates to loose leaf binders for use with perforated sheets or leaves.

The object of this invention is to provide a construction whereby sheets of various sizes and having perforations spaced at various distances can be bound together.

With this and other objects in view my invention consists of a socket adapted to be permanently fixed to the cover or folder of a loose leaf book such as a ledger or the like, and individual leaf holders removably and adjustably borne in said socket so that the number of individual holders in the socket may be regulated according to the number of perforations in the sheets used and the holders may be adjusted relative to one another according to the particular spacing of the perforations in the sheets.

My invention will be more fully understood by reference to the accompanying drawing in which similar reference characters denote corresponding parts and in which Figs. 1 and 2 are respectively top plan views of a closed and open loose leaf book equipped with my new device; Fig. 3 is an enlarged top plan view of the device proper shown attached to one of the covers of the book; Fig. 4 is a cross section on line 4—4 of Fig. 1; Fig. 5 is a section on line 5—5 of Fig. 1; Fig. 6 is a cross section on line 6—6 of Fig. 2; Fig. 7 is a plan view of the inner face of the upper cover; Fig. 8 is a cross section similar to Fig. 4 of a modified construction; Fig. 9 is a plan view of a part of the inner face of the upper cover showing a modification of a detail; Fig. 10 is a cross section on line 10—10 of Fig. 9, and Fig. 11 is a cross section on line 11—11 of Fig. 9; and Fig. 12 is a perspective view of the individual binder.

Referring to the drawing, the binder comprises a socket 10 preferably made of a strip of metal which is bent upon itself at its longitudinal edges to form opposite longitudinal grooves 10'. 11 denotes individual members or holders which are adapted to be adjustably and removably borne in the

socket 10, so that the number and spacing thereof may be easily regulated to conform with those of the perforations in the sheets used. In the present embodiment of my invention the members 11 each consist of a base portion 11' made to fit snugly in the grooves 10' of the socket 10, and a hook shaped portion 11² projecting upwardly from the base. The grooves 10' of the metal strip 10 are open at their ends 10² to allow the insertion or removal of the aforesigned individual members 11 into and from the socket 10.

The individual binding members 11 when placed with their bases 11' into the grooves 10' of the socket will be frictionally engaged thereby, so that they will be retained in working position, but can be shifted longitudinally to adjust their spacing in conformity with that of the perforations in the sheets.

The socket 10 is adapted to be permanently fixed to the inner face of a folder or cover of a loose leaf book.

In the present example I have shown a loose leaf book consisting of two separable covers 12, 13 which near the rear ends have foldable sections 12', 13'.

The socket 10 is adapted to be fixed longitudinally of and adjacent to the rear edge of the foldable section 13' of the lower cover and the removable upper cover is provided with means for engaging the free ends of the hook shaped projections 11² so as to prevent the sheets from slipping off the individual binding members 11.

For the engagement of the free ends of the hooks 11 and for the connection of the two covers the following construction is employed:

The body portion of the socket 10 is extended longitudinally at one of its ends as at 10³ and is formed with a vertical and a horizontal bend. The horizontal bend is directed inwardly or toward the socket and constitutes a tongue 10⁴. On the inner face of the foldable section 12' of the upper cover, a longitudinal groove or slot 12² is provided which when the cover is applied is adapted to engage the perpendicularly bent ends 11³ of the hooks, thereby preventing the sheets engaged by the individual binders 11 from slipping off.

At each end of the foldable section 12' of the upper cover, I provide grooved members or pockets 14, of which the one located at

the end adjacent to the tongue 10⁴ is adapted to engage the latter. A detachable U-shaped tongue 15 is adapted to be inserted into the pocket 14 at the opposite end of the tongue 10⁴ and into the socket 10. By these tongues 10⁴ and 15 the two covers are separably connected together.

Instead of the slot 12² and separate members 14 the foldable section 12' of the cover 12 may be provided with a member 16 made of a single strip of metal bent upon itself at its longitudinal edges to form a groove 16' for the engagement of the ends 11³ of the hooks 11 and sockets 16² for the engagement 15 of the tongues 10⁴ and 15.

The tongues may be retained in the pockets 14 and 10 by friction or suitable means such as snappers 17 may be used to secure their engagement.

20 In order to close the open space 18 formed between the two covers 12, 13, the upper cover may be provided with a rear extension of flexible material to form a flap 19 which may engage a pocket 20 in the lower cover, when the two covers are connected to one another, and serve as a back.

I claim:

1. A loose leaf binder, comprising a cover,

a member formed with opposite grooves, laterally curved leaf holders having flat bases frictionally engaging said grooves, the free ends of said leaf holder being perpendicular to said bases, an auxiliary cover having a slot to engage said free ends of the leaf holders, and means between said two covers for detachably connecting the latter together.

2. A loose leaf binder, comprising a cover, a member formed with opposite grooves and an extension at one end, leaf holders having flat bases frictionally engaging said groove, an auxiliary cover having a slot to engage the free ends of said leaf holder, and end pockets, one of said pockets being adapted to removably engage the said extension, and a detachable member adapted to engage the other pocket of said auxiliary cover and the said grooves for connecting the two covers together.

In testimony whereof I affix my signature 50 in presence of two witnesses.

LOUIS W. BERGMAN.
